United States Patent Office.

EDMUND F. BURROWS, OF MYSTIC RIVER, CONNECTICUT.

Letters Patent No. 92,577, dated July 13, 1869.

IMPROVEMENT IN MAST-HOOPS.

The Schedule referred to in these Letters Patent and making part of the same.

To all whom it may concern:

Be it known that I, EDMUND F. BURROWS, of Mystic River, in the State of Connecticut, have invented a new and useful Improvement in Mast-Hoops; and I do hereby declare that the following is a full, clear, and exact description of the same, reference being had to the annexed drawings, making part of this specification, in which—

Figure 1 is a perspective view of my improved hoops, showing how they are secured to the gaff-jaws, or to the saddle.

Figure 2 is a sectional elevation of the gaff, with one of its jaws and the saddle, showing how the ropes are attached thereto, and, also, the pivoted lever or guide attached thereto.

Corresponding letters refer to corresponding parts in the several figures.

This invention relates to hoops for the masts of vessels; and

It consists in the method of suspending or arranging such hoops, for the purpose of preventing them from dragging upon the masts, while the sail or the arm, or gaff to which they may be attached, is being raised or lowered, as will be more fully described hereinafter:

The usual method of suspending or attaching hoops to the gaff-jaws, or saddle, is by a single rope, attached to one point of the hoops, which leaves its opposite side free to drop down and drag against the masts, when the same are being raised or lowered, the effect of which is to cause the expenditure of a largely-increased amount of force in raising the sails, and not unfrequently the fouling and consequent stoppage of the same, when the sails are being lowered.

My invention has for its object the removal of these objections and difficulties, by attaching the hoops to the gaff-jaws and saddle A and A', by means of three or more ropes extra from the "brush-rope."

The back rope, as it is or may be termed, is attached to the lower end of the saddle, and to the back of the top hoop, or that portion thereof which is directly beneath such saddle.

The other ropes, or those upon the other sides or portions of the hoops, are to be attached to the under side of the gaff-jaws, by means of eye-bolts, which are to be placed directly under or in a line with the pivot-bolt, upon which the saddle turns, as shown at B, in figs. 1 and 2, or they may be attached directly to such pivot-bolt, by cutting away the sides of the jaws for that purpose.

From these points those ropes which are represented in the drawings at C, C', and C'', extend downwards, and are to be seized or otherwise secured to eyes upon the outer surfaces of the hoops, the ropes passing through such eyes, and on to the next hoop, to which they are to be secured in the same manner.

It will be seen, that as a consequence of the hoops being suspended at three or more parts, and connected to the gaff-jaws and saddle at the parts designated, with reference to the mast upon which they move, will always be such as to cause the smallest amount of friction thereon, and to prevent the possibility of fouling when the sails are being lowered, whatever angle the gaff or arm may assume, with reference to the mast, for the time being.

Having thus described my invention,

What I claim, and desire to secure by Letters Patent, is—

1. The arrangement of the saddle A', with reference to the gaff-jaws, and the rope C', for aiding in raising the hoops, substantially as set forth.

2. The arrangement of the eye-bolts, to which the upper ends of the suspending-ropes are attached, with reference to the pivot-bolt upon which the saddle turns, substantially as shown, and for the purpose set forth.

In testimony whereof, I have signed my name to this specification, in the presence of two subscribing witnesses.

EDMUND F. BURROWS.
